LUGGAGE

Filed Feb. 2, 1927

ALICE S. ACHESON.

Inventor

By Semmes & Semmes

Attorney

UNITED STATES PATENT OFFICE.

ALICE S. ACHESON, OF WASHINGTON, DISTRICT OF COLUMBIA.

LUGGAGE.

Application filed February 2, 1927. Serial No. 165,441.

This invention relates in general to apparel carrying containers, and more particularly has reference to a portable hat box having a novel provision for carrying foot gear or 5 other articles.

Previous to this time, there has not been provided in luggage of this character any means whereby other articles of a type having a detrimental effect on fine goods might be 10 transported in a fixed position within the container, to prevent movement and consequent soiling of the hats or other delicate wear.

It has recently become customary for women when traveling, to employ a hat box to accommodate their apparel, as a container of this sort has been found to possess greater utility than other types of traveling bags, in that it will receive head wear. Extreme difficulty has been encountered, however, in that 20 articles placed loosely in the box are liable to movement and as a result soil or rupture the fabric of the hats.

An object of this invention is to provide a 25 portable hat box having provisions for carrying other articles in a fixed position.

A further object of this invention is to provide a portable hat box having a provision for carrying footgear in a fixed position.

Another object is to permit shoes of different sizes through the instep to be carried without danger of their slipping from the supporting straps.

This invention consists in general of a 35 provision of a portable hat box having novel securing means adapted to hold footgear and prevent movement thereof, to avoid soiling or rupturing the fabric or mats or other delicate goods in the box by movement caused by 40 shocks encountered in transit.

With these and other objects in view which may be incident to my improvements, the invention consists in the parts and combinations to be hereinafter set forth and claimed, with 45 the understanding that the several necessary elements comprising my invention, may be varied in construction, proportions and arrangement, without departing from the spirit and scope of the appended claims.

In order to make my invention more clearly 50 understood, I have shown in the accompanying drawings means for carrying the same into a practical effect, without limiting the improvements in their useful applications to the 55 particular constructions, which for the pur-

pose of explanation, have been made the subject of illustration.

In the drawings forming a part of this specification:

Figure 1 is a top view of the container in 60 open position.

Fig. 2 is a side elevation view taken on line 2—2 of Figure 1.

Figure 3 is a perspective view showing the 65 mounting of the securing element.

Referring by numerals to the drawings, wherein the same elements are designated by the same numerals throughout, and more particularly to Figure 1, 1 is a body portion of a container commonly known in the art as a hat 70 box having a top or lid 2 adapted to be held on the body portion 1 by a hinge, not shown. The top is provided with projecting portions 3 adapted to fit in clasps 4 on the body portion 1 and be secured by hinged metal straps 75 5, when the lid is closed over the body portion 1. The top is also provided with a handle 6 secured to the container 1 by hinges 7.

A strap 8 composed of any suitable material such as leather is adapted to be affixed 80 internally to the sides of the body portion at a suitable angle to the horizontal, as shown in Figure 2, by sewing with a thread 9 or any other suitable mode of fixture. By placing the straps at an angle, the footgear is held in such a position that they are prevented from rubbing against and damaging the hats. Moreover by arranging the straps at an angle 85 the longest shoe can be accommodated in a hat box of ordinary height. The ends of the straps are provided with snaps 10 adapted to engage snap heads 11 suitably mounted in proper positions on the side of the body 1 of the container.

It is manifest that this invention is not 90 limited to the particular form of snaps used, as any other suitable type of fastening may be employed instead, or a strap composed of particular material such as leather. Nor is it limited to individual straps, as a single strap 100 may be mounted in the container suitably secured at one end, and the other end passed through several channel guides so that footgear or other articles may be inserted between the guides and by pulling one end of the strap 105 the entire number may be secured and the strap fastened in any desired manner.

The operation of this invention may be 110 readily understood having reference to Figure 2. The straps 8 are mounted at an an-

gle to the horizontal of the container to prevent frictional contact of the foot wear with the other contents and also to accommodate shoes of greater length than the height of the box. The plurality of fastening snaps 10 are adapted to afford a more secure fastening than a single snap and snap head, which is likely to open if undue stress is placed upon it. Yet another advantage is that the strap 10 can be in effect made longer by engaging the snap at the end of the strap only, thus permitting a heavier shoe or one with a wider instep to be carried.

There is accomplished by this invention, 15 the provision for a fastening means mounted in a hat box, whereby footgear of various sizes or other articles may be firmly and conveniently held therein, to prevent soiling or otherwise damaging hats or other delicate 20 goods carried in the box.

While I have shown and described the preferred embodiment of my invention, I wish it to be understood that I do not confine myself to the precise details of construction herein 25 set forth, by way of illustration, as it is apparent that many changes and variations may be made therein, by those skilled in the art, without departing from the spirit of the in-

vention, or exceeding the scope of the appended claims.

I claim:

1. In a container for head wear, means to secure footgear comprising adjustable, flexible and non-expansile straps mounted at an angle to the horizontal.

2. In a container for head wear having flexible straps adapted to receive footgear, means to secure adjustably the straps comprising a plurality of fastening snaps whereby the straps may be adjusted to shoes of varying width.

3. In a container for head wear, flexible straps designed to receive footgear having one end secured to the upright walls of the container, the other end adapted to be secured by one of a plurality of fastening snaps, whereby adjustment to size may be effected.

4. In a container for headwear, flexible straps designed to receive footgear angularly disposed to the horizontal having one end fixedly secured to the upright walls of the container, the other end adapted to be fastened by a removable fastening means to the container.

In testimony whereof I affix my signature.
ALICE S. ACHESON.
